UNITED STATES PATENT OFFICE.

JOSEPH ALBERT HILL, OF SHEFFIELD, ENGLAND.

KNIFE-MACHINE.

1,257,232.

Specification of Letters Patent. Patented Feb. 19, 1918.

Application filed June 19, 1917. Serial No. 175,671.

To all whom it may concern:

Be it known that I, JOSEPH ALBERT HILL, a subject of the King of England, residing in Sheffield, in the county of York, England, 5 have invented certain new and useful Improvements in Knife-Machines, of which the following is a specification.

This invention is for improvements in or relating to knife-machines and is particularly applicable to machines for sharpening knives although it can be applied to knife-cleaners.

The present invention has reference to the means for supporting knives of different 15 lengths in a machine of the type wherein the blade to be sharpened is supported on a reciprocating carrier operated by a crank-pin on a wheel which is rotated by the driving means of the machine. The carrier 20 moves the blade backward and forward between opposed sharpening-disks which are rotated by the same driving means, and by the reciprocations of the carrier the whole length of the blade is brought into contact 25 with the abrading surfaces of the disks.

For the purpose of this invention, a machine such as described above is provided with a variable-throw device which does not itself form part of the invention as it is a 30 well-known mechanism. This device comprises a disk which is mounted concentrically with the crank-pin wheel for reciprocating the blade-carrier. This disk is angularly adjustable relatively to the crank-pin 35 wheel and the crank-pin is mounted in a radial slot in the wheel and has a foot which extends into a cam-groove on the disk. Means are provided for locking the disk to the wheel in different angular positions so 40 as to vary the throw of the reciprocating carrier according to the length of the knife-blade which is to be sharpened.

According to the present invention, a 45 knife-machine of the type described and having a crank-pin wheel with a variable-throw crank as described, is provided with an adjustable limiting-stop on the knife-carriage, which stop engages the end of the knife to situate lengthwise on the carriage, 50 for the purpose of bringing knives of different lengths to a central position thereon so that once the stop is adjusted for any given length of knife, all knives of such length can be immediately brought to such 55 position on the carrier with the consequent proper adjustment of the throw, and the

whole length of the edge will be brought into contact with the sharpening disks without the ends being at any time entirely withdrawn from the same during the sharpen- 60 ing operation.

In the accompanying drawings which illustrate one method of carrying out this invention:—

Figure 1 is a front elevation of the knife-sharpening machine showing the parts to which the present invention relates; 65

Fig. 2 is a plan of the said parts;

Fig. 3 is a face view of the cam disk for varying the throw of the crank; 70

Fig. 4 is a face view of the reverse side of the cam disk shown in Fig. 3; and

Fig. 5 is a section through the crank-pin wheel and the parts immediately associated therewith. 75

The same letters indicate the same parts throughout the drawings.

The machine is provided with two pairs of disks A, A¹, though in Fig. 1 only one disk of each pair is shown and these are 80 not illustrated in Fig. 2 in order that confusion might be avoided, but it will be appreciated that there would be two disks A placed edge-to-edge and two disks A¹ placed edge-to-edge and co-axially alined with the 85 corresponding disks A, both pairs of disks being driven from the operating handle of the whole machine.

To adapt the carriage to receive knives instead of safety-razor blades, a table B is 90 mounted on the guide-plate B¹, and on the table is a clip B² into which the blade of the knife to be sharpened is pressed; the table B, guide B¹, and clip B² thus constitute the carriage for the knives to be sharpened. Conveniently the table is adjustable 95 vertically relatively to the guide B¹ by means of arms B³ secured by thumb-nuts B⁴.

The end of the guide B¹ has a vertical extension B⁵ which is slotted at B⁶ to receive 100 a crank-pin C. The crank-pin instead of being fixed is free to move in a radial slot D¹ provided in the carrying-wheel D. The pin C is shouldered at C¹ to prevent it from passing through the slot D¹ and is secured 105 in place by a screw C² which enters the back of the pin and has a washer C³ under its head to prevent the pin from being drawn forward out of the slot D¹.

The wheel D is made fast on a spindle 110 E which is rotatably mounted in a supporting-arm E¹, and free on the spindle, and

thus mounted concentrically with the wheel D is a disk F. The disk F is provided with a cam-groove F¹ on that face which is toward the wheel D, which cam-groove receives 5 the head of the screw C². The disk has a milled edge so that it can be easily turned by the fingers, and on that side which faces away from the wheel D it is provided with a series of recesses F² which engage a 10 detent G. The detent is secured in any convenient manner to the spindle E and is made of resilient material. It has a projection G¹ on that face which is toward the disk F, so that when the disk is turned to bring 15 any one of the recesses F² opposite this projection, the projection springs into the recess and the detent thus locks the cam disk against accidental displacement relatively to 20 the wheel D although it does not prevent hand-adjustment.

At one end of the table B is a limiting-stop H in the form of a right-angled plate, one side of which lies flush upon the table B and the other side projects vertically 25 therefrom. The stop is carried in guides H¹ so that it can slide endwise along the table, and beneath the table is fixed a spring detent H². The under-side of the stop is provided with a series of recesses H³ and the 30 projection of the detent H² extends through the table so that it can enter any one of these recesses when brought opposite it. The stop has a finger-piece H⁴ whereby it can be slid backward and forward through 35 the guides H¹. The stop H is provided with a series of indicating-points numbered 1—5 which correspond to the recesses F² on the disk F which are also numbered 1—5.

The operation of this carriage is as follows:—

If the knife is the full length the machine is intended to take, as is supposed in the case shown in the drawings, the stop H is moved back as far as it will go so that the 45 indication marked "1" appears at the side of the guide H¹ and the disk F is turned to bring the recess marked "1" under the detent G. A knife is then put in place in the clip B² and its end butted against the 50 stop H. With the parts so arranged, it will be found that when the handle of the machine is turned, the knife will be so reciprocated that the whole length of its edge is brought into contact with the sharpening-disks A, A¹, without the ends leaving the 55 disks during sharpening. If the ends were to leave the disks during sharpening there is a tendency for them to strike against the disks and so damage the machine or throw 60 the knife out of the clip. For a shorter knife, the stop H is advanced to such position that it butts against the end of the blade when the shorter knife is placed on the carriage with the clip in mid position along 65 the length of the knife, and then the disk

F is turned to bring the recess F² under the detent G whose number corresponds with the number which will then appear on the stop H at the side of the guide H¹.

Where several lengths of knives are used, 70 it soon becomes known to the operator which numbers correspond to the different lengths and thus adjustment can be made immediately and once this adjustment is effected for any length of knife, each knife of that 75 length has only to be thrust in until it butts against the stop, when all the parts will be in proper position for sharpening.

What I claim as my invention and desire to secure by Letters Patent is:—

1. In a knife-machine, the combination of, a carrier having spring jaws to engage the blade of a knife by its sides, guides for the carrier to permit it to slide in the lengthwise direction of the knife, a variable-throw 85 crank for reciprocating the carrier along the guides, means for setting the throw of the crank to suit the length of knife to be operated upon, and an adjustable limiting-stop on the knife-carriage so situated as to 90 engage the end of the knife when pushed into the carriage, thus to situate it lengthwise on the carriage, a rotary tool mounted so that its periphery bears against the side of the blade and at the edge thereof during 95 the whole of its reciprocating movements with the carrier, and means operatively connecting the carrier and tool so that the tool continuously rotates against the blade as the carrier reciprocates upon its guides, substantially as and for the purpose described. 100

2. In a knife-machine, the combination of, a carrier having spring jaws to engage the blade of a knife by its sides, guides for the carrier to permit it to slide in the lengthwise direction of the knife, a variable-throw 105 crank for reciprocating the carrier along the guides, means for setting the throw of the crank to suit the length of knife to be operated upon, and an adjustable limiting-stop on the knife-carriage so situated as to engage the end of the knife when pushed into the carriage thus to situate it lengthwise on the carriage, a rotary tool mounted 110 so that its periphery bears against the side of the blade and at the edge thereof during the whole of its reciprocating movements with the carrier, and means operatively connecting the carrier and tool so that the tool continuously rotates against the blade as the 115 carrier reciprocates upon its guides, the movable stop and the movable member for varying the throw of the crank being both provided with indicating means to show the proper setting for the stop for any particular selected throw of crank and vice versa, substantially as and for the purpose described. 120

3. In a knife-machine, the combination of, a reciprocating carrier having gripping 130

means to engage the blade of a knife by its sides, a crank-disk having a slot which extends from a point near the center toward the periphery, a crank-pin mounted to slide in this slot but held against endwise displacement therefrom, a second disk mounted at the side of the first and having in that face which is toward the first disk a cam-groove which engages a projecting end of the crank-pin base, means for setting this cam-disk at any chosen angular position relatively to the slotted disk for varying the throw of the crank-pin, means operatively connecting the crank-pin and the carrier so that it is reciprocated when the disk is ro-

5 tated, the throw of the carrier varying according to the adjustment of the crank-pin, and an adjustable limiting-stop on the knife-carrier so situated as to engage the end of the knife to situate it lengthwise on the carriage, substantially as and for the purpose described. 20

10 In testimony whereof I have signed my name to this specification in the presence of two subscribing witnesses.
